UNITED STATES PATENT OFFICE.

HARLEY BROOMHALL, OF SHELBY, OHIO, ASSIGNOR TO THE SHELBY METAL PRODUCTS COMPANY, OF SHELBY, OHIO, A CORPORATION OF OHIO.

LATCH AND DOGGING MEANS THEREFOR.

Application filed April 23, 1926. Serial No. 104,134.

This invention relates to improvements in means for dogging a door latch or the like.

The primary object of the invention is to provide means for automatically maintaining the latch under tension in yielding operative position, for positively and constantly maintaining the latch in fixed operative position and positively and constantly maintaining the latch in fixed operative position at the will of the operator, by the manipulation and adjustment of one unit of the means.

Another object of the invention is to provide a means for dogging a door latch which can be applied to the side or end of the body of the door latch, thereby leaving the face of the latch free from any interference with the operation of the latch and presenting a smooth surface for finishing purposes.

Another object is to construct a dogging member of sheet metal or the like which is adapted to be used and operated in cooperation with a latch mechanism constructed of sheet metal, to provide a complete latch and latch mechanism that is simple in operation and construction, thereby saving labor and material and providing smooth and polished surfaces of the parts for finishing purposes.

Further objects are to provide means for using the same tension means, that maintains the latch mechanism in yielding position, for the purpose of forcing and holding dogging member in close contact with the body of the latch, to prevent play between the parts, to provide means for guiding the dogging member when it is being adjusted to different positions and for supporting it within the body.

These and other objects are attained by the mechanism illustrated in the accompanying drawing in which:—

Figure 1 is a bottom plan view of the latch and dogging mechanism showing the yielding operative position of the latch in full lines and the dogged position of the latch in dotted lines.

Figure 2 is a bottom plan view of the latch and dogging mechanism showing the latch positively and constantly held in fastened position by the dogging mechanism.

Figure 3 is a sectional view of Figure 2 taken on the line 1—1 of Figure 2.

Figure 4 is an end view of Figure 1 taken on the line 3—3.

Figure 5 is a sectional view of Figure 1 taken on the line 2—2.

Figure 6 is an end view of Figure 1 with the button and pin removed to more clearly show the relation of the slots in the casing and fastening member.

Figure 7 is a bottom plan view of a part of the latch and fastening mechanism showing in full lines the latch positively and constantly held in withdrawn position by the fastening mechanism and the off position of the dogging member in dotted lines.

In the drawings the dogging mechanism is shown applied to and cooperating with a latch mechanism, that is the subject matter of an application filed in the Patent Office on April 14, 1926, bearing Serial No. 101,901 and to which reference is made for the specific description of same.

In this application the latch mechanism of the above identified application will be described more or less generically in connection with a dogging mechanism which is associated therewith and is the subject matter of this application.

The latch mechanism is enclosed, except at the bottom, in a hollow body comprising a top 1 having side members 2, 3, 4 and 5 made integral therewith. The side members 4 and 5 are provided with integral flanges 6 and 7 having apertures 8—8 formed therein to receive screws or the like, to fasten the body to a door or the like. The flanged members 6 and 7 are preferably turned at right angles at their edges as shown at 9 and 10. The complete body as described is constructed and pressed to form from an integral piece of sheet metal.

The top portion 1 of the body is provided with an aperture 11 which is surrounded by an annular rib 12. A latch member 13 is mounted to slide on the bottom face of the part 1 of the body and is provided with an elongated slot 14. The margin of the latch member forming the ends of the slot 14 contact with the annular rib 12 and provides a stop to limit the sliding movement of the latch member in both directions.

A square aperture 15 is provided in the side portion 2 of the body to receive for sliding movement, the latch 16 of the latch member 13. A U-shaped cam member 17 is mounted to pivot in the casing immediately adjacent

the latch member 13 and is normally positioned thereon as shown in Figure 1 in full lines to lie in contact with the upturned portion 18 of the latch member. When positioned as shown in dotted lines in Figure 1 the latch 16 of the latch mechanism 13 is in yielding dogged position.

The cam member is connected to one end of a stud shaft 19 for pivotal movement and 10 is fastened thereto by riveting as shown at 20. The latch member 13 it will be observed is movably held in position between the portion 1 of the body and the cam member 17. The free end of the stud shaft 19 is provided with a lever 21. When movement is imparted to the lever 21 in either direction by the ends 22 or 23 of the cam member, the latch of the latch member is forced to inoperative position as shown by dotted lines in 20 Figure 1. A conventional strike 24 is associated with the latch when the latch is actuated to operative position.

The latch mechanism herein described briefly is the subject matter of the pending 25 application herein identified. It is described herein to show the preferred latch mechanism to which the present invention is applied.

To provide a dogging means for the latch 30 mechanism, a slot 25 and an aperture 26 are formed in the side 3 of the body. A sliding dogging member 27 having a right angle projecting portion 28 extending horizontally therefrom at one end and another similar 35 portion 29 extending horizontally from the other end is provided. The free end of the portion 29¹ is bent laterally to form a contact member substantially U-shaped with a portion thereof, presenting a flat surface 29². The projecting portions 28 and 29 are cut 40 away at 30 and 31 to provide clearance for the latch member to slide underneath the projecting portions of the dogging member when the latch is moved to unfastened position.

The dogging member 27 is also provided 45 with a slot 32 and an aperture 33. The U-shaped end of the latch member also serves to align the projecting portion of the dogging member with the slot and opening in the upturned portion 18 of the latch mechanism. The sliding dogging member 27 is placed in juxtaposition to the side 3 of the body and is adapted to slide back and forth in the body 50 in contact with the side 3. To provide means for sliding the dogging member 27 back and forth manually, a button 34 is provided having a collar 35 to press against the dogging member 27. The button is provided with a shank 36.

The shank 36 of the button is passed 60 through the slot 25 and is inserted into the aperture 33 in the dogging member and is riveted or otherwise fastened thereto. Actuation of the button 34 in either direction 65 im- parts movement to the sliding dogging mem-

ber for positioning same for the purpose intended. To hold the latch in normal or yielding operative position the following elements are employed: A pin 37 having a collar 38 is provided. One end of the pin is passed through the slot 32 in the dogging member and inserted in the aperture 26 formed in the side 3 of the body.

The opposite end of the pin is inserted in an aperture 39 formed in the upstanding portion 18 of the latch member. The aperture 39 is preferably made larger than the pin, to permit efficiency and convenience in inserting the end of the pin in the aperture 26 of the side 3 and 39 of the upturned portion 80 of the latch member 18. The upturned portion 18 of the latch member is provided with a slot 40 and is cut away at one end as indicated by reference numeral 41.

An expansible spring 42 is mounted on the pin 37 to exert a yielding tension against the upturned portion 18 of the latch member and against the dogging member by pressing the collar 38 against the dogging member forcing it in close contact with the side 3, thereby preventing play of the parts and holding same in position. The expansible spring 42 in exerting a tension against the upturned portion 18 of the latch member also forces and holds the latch of the latch mechanism in normal yielding operative position as shown in Figure 1 in full lines. A door knob shaft 43 is connected to a part 44 of the cam member by a cotter pin 45, thereby permitting operation of the latch from either side of the door or the like.

When it is desired to permit the latch to be held in normal position or in other words in yielding operative position the dogging member 27 is adjusted to the position shown in full lines in Figure 1, which permits the lever or the like to operate the cam member to actuate the sliding latch member to be moved under tension of the spring 42 to inoperative position as shown in dotted lines in Figure 1.

When the latch member is moved to unfastened position against the tension of the spring 42 the projecting portion 28 passes through the slot 40 and the projecting portion 29 clears through the opening provided by cutting away a part of the upturned portion 18 of the latch member as shown at 41.

In Figure 2 the dogging member is shown shifted or adjusted from its normal position as shown in Figure 1, to a position to permit the projecting portions 28 and 29 to line up with the body of the upturned portion 18 of the latch member or to contact with the face thereof, thereby positively and constantly maintaining the latch in non-movable position.

While the dogging member is being adjusted to a position in line with the upturned portion 18 of the latch member for constantly and positively maintaining the latch in fixed

position, the latch member is held in its normal yielding operative position by the tension means and after adjustment is held constantly and positively in fixed position as shown in Figure 2.

When it is desired to maintain the latch in withdrawn position positively and constantly, the latch member is actuated against the tension of the spring 42 to the position shown in Figure 1 in dotted lines and Figure 7 in full lines and the dogging member while held in said position is shifted or adjusted to permit the flat portion 29² of the contact member 29¹ to engage the end 29³ of the upturned member 18, thereby fixing the latch positively and constantly in withdrawn position as shown in Figure 7 in full lines.

The dogging mechanism as shown in the drawings is preferably applied to a latch mechanism constructed as shown in the drawings. It is not intended however, to limit the dogging mechanism shown herein to its association with the specific latch mechanism shown, as it is obvious that the principle involved in the dogging mechanism described herein can be applied and associated with other latch mechanisms, without departing from the principle of the invention.

It will be noted that the dogging member as constructed and applied to the latch mechanism provides means of operating from the end or side of the body containing the latch mechanism, leaving the top of the body free and unobstructed, to permit the operation of the latch mechanism without interference.

I claim:

1. In a latch, a body, a latch member slideable in the body, means for securing the latch member in projected or retracted position relative to the body, and spring means cooperating with said latch member and with said securing means and serving to normally project the latch member relative to the body and to hold the securing means against casual displacement.

2. In a latch, a body, a latch member slideable in the body and including a latch nose and an inner outstanding wall, a dogging element slideable on the body to and from an operative position, said element having spaced projections engaging said wall to prevent unlatching movement of the latch member when the element is in operative position and the latch nose projected, one of said projections being formed to engage one edge of said wall when the element is in operative position and the latch nose withdrawn to prevent latching movement of such latch member.

3. In a latch, a body, a latching member including a latch nose and an outstanding wall,

a dogging element slideable on the body and cooperating with said wall to prevent movement of the latching member from the position occupied when the dogging element is actuated, and a spring serving to normally project the latch member, said spring bearing on the dogging element to prevent casual displacement of the latter.

4. A latch member including a body, a latch movable therein and including a latch nose and an outstanding wall, an operator for the latch cooperating with the wall to withdraw the latch nose, a spring cooperating with said wall to move the latch nose into projected position, and a dogging element slideable on the body and having spaced projections to be interposed into the path of said wall when the latch nose is projected to prevent movement of the latch member by the operator, one of said projections having an offset portion to engage one edge of said wall when the latch member is withdrawn, to thereby prevent movement of the latch member under the action of the spring.

5. In a latch, a body, a latch member including a latch nose and an outstanding wall movable in the body, an operator cooperating with the wall to withdraw the latch nose, a spring cooperating with the wall to project the latch nose, a dogging element slideable on the body and adapted for manual operation to either of two positions, said spring bearing on the dogging element to prevent casual displacement thereof when in either position, spaced projections carried by the dogging element adapted, when the nose is projected and the dogging element in operative position, to be interposed in the path of and prevent movement of said wall, whereby to hold the latch nose fixed in projected position.

6. In a latch, a body, a latch member including a latch nose and an outstanding wall movable in the body, an operator cooperating with the wall to withdraw the latch nose, a spring cooperating with the wall to project the latch nose, a dogging element slideable on the body and adapted for manual operation to either of two positions, said spring bearing on the dogging element to prevent casual displacement thereof when in either position, spaced projections carried by the dogging element adapted, when the nose is projected and the dogging element in operative position, to be interposed in the path of and prevent movement of said wall, one of said projections being formed to engage with one edge of said wall when the latch nose is withdrawn and the element is in operative position to thereby hold the latch nose in inoperative position.

In testimony whereof I affix my signature.
HARLEY BROOMHALL.
